UNITED STATES PATENT OFFICE.

REUBEN HILT, OF WEST SOMERVILLE, MASSACHUSETTS.

OSCILLATING LEVER FOR OPERATING PUMP-PISTONS, &c.

1,091,136.

Specification of Letters Patent. Patented Mar. 24, 1914.

Application filed October 8, 1913. Serial No. 794,136.

To all whom it may concern:

Be it known that I, REUBEN HILT, a citizen of the United States, and resident of West Somerville, in the county of Middlesex and State of Massachusetts, have invented certain new and useful Improvements in Oscillating Levers for Operating Pump-Pistons, &c., of which the following is a specification.

10 This invention relates to an oscillatory lever employed to impart rectilinear movement to a pump piston or other reciprocating device.

The specific embodiment of the invention shown in this application is a lever employed in a monotype machine for imparting motion to the piston of a pump employed for moving melted type metal, one arm of the lever being bifurcated and provided with cheek pieces which are movably engaged with the divisions of the bifurcated lever arm so that they may turn or rock on said divisions, the cheek pieces being provided with bearing faces which engage 20 shoulders on a piston rod or plunger, the construction and arrangement being such that when the lever is oscillated it imparts through the cheek pieces a rectilinear reciprocating movement to the plunger, the latter being in sliding engagement with the cheek pieces to compensate for the difference in direction between the rectilinear path of the plunger and the curvilinear path of the cheek pieces.

30 The invention has for its object to provide an improved construction of the said cheek pieces for the purpose of connecting them durably with the lever in such manner as to prevent liability of loose wabbling motion of the cheek pieces, and to enable the cheek pieces so nearly to inclose the lever arms that they form boxes adapted to confine graphite or other refractory lubricant between the internal surfaces of the cheek 40 pieces and the external surfaces of the lever with which they are in rubbing contact.

When my invention is embodied in a lever for operating the type metal pump plunger of a monotype machine, the cheek pieces and the portions of the lever on which they bear are maintained at such a high temperature that ordinary combustible lubricants 50 cannot be employed.

My improvement hereinafter described enables the lubrication of the cheek pieces by graphite to be suitably maintained.

The invention consists in the improvements which I will now proceed to describe and claim.

Of the accompanying drawings which form a part of this specification,—Figure 1 is a side elevation of a pump lever embodying my invention; Fig. 2 is a plan thereof partly in section as on the line 2—2 of Fig. 1; Fig. 3 is a sectional detail 60 as on the line 3—3 of Fig. 2; Figs. 4 and 5 are perspective views of the respective parts of one of the cheek pieces.

Similar reference characters indicate the same parts in all the figures.

In the drawings,—6 designates a lever 70 adapted to oscillate on a central fulcrum between its arms, the lever being oscillated by power applied in any suitable way to one of said arms. The opposite arm which imparts motion from the lever to a plunger or piston rod 7, is bifurcated to form divisions 8, each having a segmental edge 9 and a circular socket or bearing 10 concentric with said edge.

To each division 8 is applied a cheek piece 80 which is adapted to rock on the segmental edge 9, the latter constituting a bearing for the cheek piece, and being provided with a trunnion which enters and is adapted to 85 rock in the bearing 10.

Each cheek piece comprises a flat sided body portion 11 adapted to bear on the inner side of one of the lever divisions 8, a trunnion 12 projecting from one side of the body 90 portion 11 and formed integrally therewith or attached rigidly thereto, the trunnion being fitted to turn in the socket 10, and a substantially U-shaped flange 13 having a segmental inner face 14, the greater portion 95 of which is concentric with the trunnion 12. The flange 13 has upper and lower flat faces 15 which abut against opposed shoulders 16 on the piston rod or plunger 7, said rod having a reduced squared portion 17 located 100 between the two cheek pieces. Each cheek piece also includes a cap piece 18 which is a flat metal plate having the same marginal contour as the flange 13, and adapted, when placed upon the outer edge of said flange, 105 to close the outer side of the space between the segmental inner wall 14 and trunnion 12.

The cap piece 18 is placed on the outer edge of the flange 13 after the latter has been applied to the lever. The cap piece is 110 then firmly attached to the flange, preferably by a welding operation, the welding

being caused by the application of the flame of a welding torch to the joint between the flange and the cap plate. If desired, however, the cap plate may be attached by electric welding or brazing. The attachment of the cap, as described, converts the cheek piece into a box which practically incloses the segmental end portion of the lever division to which the cheek piece is applied.

10 The cap piece bears closely against the outer side of the lever division 8, and while permitting the cheek piece to oscillate to the extent required, it prevents any loose lateral wobbling motion of the cheek piece, and at 15 the same time, is adapted to confine graphite inserted between the contacting surfaces of the cheek piece and lever.

It will be seen that the cheek piece and the cap piece united thereto as described, 20 constitute practically a single unitary part having no member or members liable to be loosened or disconnected, no screws, rivets or other separable fastening devices being employed in securing the two cheek pieces 25 to the lever.

It is obvious that my invention may be embodied in a single lever arm 8 and single cheek piece secured thereto, as described.

I claim:—

An oscillatory lever or arm having a transverse circular socket, a segmental bearing edge substantially concentric with the socket and a cheek piece formed to bear on one side of the lever and having a trunnion fitted to turn in said socket, a flange having a segmental inner face in sliding contact with the segmental edge face of the lever and external faces formed to engage shoulders on a movable rod, and a cap piece attached as described to the outer edge of said flange and forming, with the cheek piece and flange, a box inclosing the portion of the lever having the segmental edge.

Signed at Boston, in the county of Suffolk and State of Massachusetts, this seventh day of October, A. D. 1913.

REUBEN HILT.
